(57) **CLAIM**

The ornamental design for a spice mill as shown and described.

DESCRIPTION

FIG. 1 is an upper perspective view of a spice mill showing my design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines and areas within the broken lines in FIG. 7 depict portions of the spice mill that form no part of the claimed design.

1 Claim, 7 Drawing Sheets
